(57) **CLAIM**

The ornamental design for an optical device, as shown and described.

DESCRIPTION

FIG. 1 is a rear-left-top perspective view of a first optical device embodying the new design;

FIG. 2 is a front-right-top perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a rear-left-top perspective view of a second optical device embodying the new design;

FIG. 10 is a front-right-top perspective view thereof;

FIG. 11 is a rear elevational view thereof;

FIG. 12 is a front elevational view thereof;

FIG. 13 is a right side elevational view thereof (with a left side substantially identical to the right side elevational view); and,

FIG. 14 is a bottom plan view thereof.

The broken lines in the figures are shown for the purpose of illustrating environmental matter and form no part of the claimed design.
